UNITED STATES PATENT OFFICE.

WILLIAM C. MARTIN, OF NEW YORK, N. Y.

MOVING-PICTURE APPARATUS.

1,169,176.

Specification of Letters Patent. Patented Jan. 23, 1916.

Application filed July 15, 1915. Serial No. 39,963.

To all whom it may concern:

Be it known that I, WILLIAM C. MARTIN, a citizen of the United States, and a resident of the city of New York, county of Bronx, and State of New York, have invented certain new and useful Improvements in Moving-Picture Apparatus, of which the following is a specification.

The invention relates to moving pictures. 10 In present usage two complete apparatuses are employed for running feature plays of more than one reel.

The object of the invention is to effect an economy by making possible practically continuous projection with but a single lamp house and a single motor. To this end two film mechanisms are combined with a single lamp house or source of light and a single motor, in such manner that operative relations may be established quickly between either of the said mechanisms and the lamp house and motor. Preferably the film mechanisms are mounted for guided movement, the lamp house and motor being stationary.

25 In the accompanying drawings illustrating the invention schematically: Figure 1 is a front view of the apparatus with portions broken away; and Fig. 2 is a side view thereof.

30 The lamp house or source of illumination is designated 1. It may be supported by a pedestal 2, which may also carry a transverse channeled beam or track 3. This track constitutes means for supporting and guiding two film mechanisms 4 and 5, as indicated in Fig. 2. The term film mechanism is to be understood as including the "machine head" with the film magazines and other usual adjuncts. In the present instance, the two mechanisms are represented as connected in spaced relation by bars 6. The means for shifting the mechanisms is represented for illustrative purposes as a lever 7 connected with one of the mechanisms by a link 8.

In Fig. 1 the parts are shown in intermediate position with neither of the film mechanisms in operative relation to the lamp house and motor, but it will be understood that by throwing the lever to the left mechanism 4 may be moved into such relation, while movement of the lever in the reverse direction will serve to move mechanism 5 into the path of the beam of light and to remove the mechanism 4 therefrom. Suitable

motion-limiting means, represented by a stop 9 at the right of Fig. 1, is preferably provided for bringing the mechanisms to rest in exact position.

The common driving motor for the mechanisms is represented diagrammatically at 10, located centrally with respect to the mechanisms. The parts 11 represent cone clutch elements on opposite ends of its armature shaft, which engage alternately and automatically with complementary clutch elements 12 carried by said mechanisms. The clutch elements 12 are shown as united with wheels 13 carried by bars 14 projecting downward from the mechanisms. Over these wheels pass endless driving connections 15 to upper wheels 16, from which the film engaging parts are driven by suitable connections not necessary to illustrate. The relations are such that when the mechanism 4 is shifted into operative relation to the lamp house it is also connected with the motor, the mechanism 5 by the same operation being displaced from in front of the source of light and disconnected from the motor. Conversely, when the mechanism 5 is in operative relation to the lamp house it is also connected with the motor, and the mechanism 4 is out of operative relation to both.

It will be understood that the construction and arrangement of parts herein illustrated is largely diagrammatic and that many changes may be made and numerous refinements introduced in practice.

What is claimed as new is:

1. Moving picture apparatus, comprising a lamp house, two film mechanisms movably supported and guided so as to be movable alternately into operative relation to the lamp house, and driving means adapted to be connected automatically with each of said mechanisms when brought into said operative relation.

2. Moving picture apparatus, comprising a lamp house, a track, two film mechanisms mounted for movement on said track, a driving motor, and means for shifting said mechanisms alternately into operative relation to the lamp house and the motor.

3. Moving picture apparatus, comprising a single lamp house, two film mechanisms, mechanical provisions for relative guided movement between said lamp house and film mechanisms, a single driving motor, and means whereby said motor is automatically

connected and disconnected with the film mechanisms according as the latter are in or out of operative relation to the lamp house.

4. Moving picture apparatus comprising 5 two film mechanisms, a single motor for driving the same, a single lamp house, and mechanical provisions for relative guided movement between said film mechanisms, lamp house and motor whereby to establish 10 operative relations between said film mechanisms alternately, on the one hand, and the lamp house and motor on the other hand.

5. Moving picture apparatus comprising a single motor and a single lamp house, two 15 film mechanisms, and means for supporting and guiding said film mechanisms for movement so that either may be brought into op-

erative relation to the lamp house and motor.

6. Moving picture apparatus comprising 20 a single motor and a single lamp house, two film mechanisms, means for supporting and guiding the same, and means for simultaneously shifting the film mechanisms so as to connect the same alternately with the 25 motor in proper projecting relation to the lamp house.

In witness whereof, I have hereunto set my hand this 1st day of July, 1915.

WILLIAM C. MARTIN.
